2,379,351

CONVEYER

John H. Hampton, Oaklyn, N. J., assignor to
 Beaumont Birch Company, Philadelphia, Pa., a
 corporation of Pennsylvania

Application February 11, 1944, Serial No. 521,906

3 Claims. (Cl. 198—171)

The principal object of the present invention is to simplify and improve the construction and operation of conveyers, more particularly in respect to the chains thereof.

Other objects of the invention will appear from the following description at the end of which the invention will be claimed.

In the following description reference will be made to the accompanying drawing forming part hereof and in which,

Figure 1 is a transverse vertical section of a conveyer embodying features of the invention; and

Figure 2 is a cross sectional view taken on the line 2—2 of Figure 1.

Referring to the drawing, the conveyer chain includes links 1 disposed in pairs and pivot pins 2 connecting the ends of the pairs of links and rollers 3 on the pivot pins between the links 1. 5 are right angle bend elements secured at one of their ends to the pivot pins and they are shown as having shoes 6 at their other ends. The right angle elements are shown as of tubular form and mounted on the pivot pins and detachably secured thereto by pins 7. The described assemblages constitute flight portions. 7^a are tie bars secured to the flight portions and disposed in range of the links of the chain and they operate to limit the pivotal motion of the flight portions in one direction. In some cases it is desirable to connect the tie bars adjustably with the flights so that their range of movement may be increased or diminished. 8 are vertically disposed working and return conduits and they include a return bend. One of the adjacent walls 9 of each of the conduits merge into a single partition wall 10 at the return bend. 11 is a discharge opening provided in the outer wall of the working conduit near the return bend. 12 is a sprocket wheel pivotally mounted at the return bend. The teeth of this wheel are notched at their ends 13 for engagement with the rollers 3 and the roots of these teeth are notched as at 14 for the accommodation of the tie bars 7^a. The partition wall 10 is forked or bifurcated for the accommodation of the sprocket wheel and at its end it contacts with the axle or journal of the sprocket wheel.

From the foregoing description it will be observed that the pivot pins 2 perform the double function of connecting the links and flight portions. Furthermore, in the event of breakage of

the flight portions they can be readily repaired.

It may be remarked that the rollers 3 greatly diminish frictional resistance and, therefore, effect a reduction in the power required for operating the conveyer.

I claim:

1. In a conveyer, the combination of a conveyer chain having links disposed in pairs and pivot pins connecting the ends of the links and rollers on the pivot pins between the links, right angle bend elements constituting flight portions secured at one of their ends to the pivot pins and having shoes at their other ends, tie bars secured to said flight portions and disposed in range of the links of the chain and operative to limit the pivotal motion of the flight portions, vertically disposed working and return conduits including a return bend and spaced adjacent inner walls which merge into a single partition wall at the return bend, a discharge opening provided in the outer wall of the working conduit near the return bend, a sprocket wheel located at the end of the partition wall and having teeth for engagement with the rollers on the pivot pins, said sprocket wheel being recessed for the accommodation of the tie bars, and said partition wall being forked to accommodate the sprocket wheel.

2. In a conveyer, the combination of a conveyer chain having links disposed in pairs and pivot pins connecting the ends of the links, and rollers on the pivot pins between the links, right angle bend elements secured at one of their ends to the pivot pins and constituting flight portions, and tie bars secured to said flight portions and disposed in range of the links of the chain and operative to limit the pivotal motion of the flight portions.

3. In a conveyer, the combination of a conveyer chain having links disposed in pairs and pivot pins connecting the ends of the links and rollers on the pivot pins between the links, right angle bend elements secured at one of their ends to the pivot pins and constituting flight portions, tie bars secured to said flight portions and disposed in range of the links of the chain and operative to limit the pivotal motion of the flight portions, a sprocket wheel constructed for engagement with the rollers and notched for the accommodation of the tie bars.

JOHN H. HAMPTON.
